AMPLIFICATION SYSTEM

Walter Soller, Cincinnati, Ohio, assignor of one-half to William H. Woodin, Jr., Tucson, Ariz.

Application December 5, 1938, Serial No. 244,123

14 Claims. (Cl. 179—171)

My invention relates broadly to electron tube amplification systems and more particularly to a balanced circuit arrangement for electron tube amplifiers.

This application is a continuation-in-part of my application Serial No. 732,170, filed June 23, 1934, for Balanced electron tube amplifier, now Patent 2,166,184, granted July 18, 1939.

One of the objects of my invention is to provide a balancing circuit for four and five element electron tube amplification systems having a high degree of stability.

Another object of my invention is to provide a circuit arrangement for multiple electrode twin tubes for amplification of electric currents under conditions of high stability.

Still another object of my invention is to provide a circuit arrangement for amplification systems in which a high degree of amplification may be effected while maintaining the operation of the circuits in highly stabilized condition and balancing the circuit by use of an auxiliary electrode introduced into the electrode assembly of the tube with the circuit so arranged that the algebraic sum of the instantaneous voltage values in different parts of the circuit is zero in the balanced condition of the circuit.

Other and further objects of my invention reside in the production of a circuit arrangement for an electron tube amplification system as set forth more fully in the specification hereinafter following by reference to the accompanying drawings, in which:

Fig. 1 diagrammatically shows a circuit arrangement embodying the power source balancing principle of my invention; Fig. 2 shows a modified circuit arrangement embodying this principle; Fig. 3 shows a coupling system for multiple electrode tubes arranged in accordance with my invention; Fig. 4 illustrates the application of my invention to three electrode electron tubes of twin arrangement; Fig. 5 is a circuit arrangement showing the application of my invention to electron tubes of the twin pentode type; Fig. 6 is a modified circuit arrangement illustrating the application of my invention in coupling multiple electrode electron tubes while maintaining stabilized operation of the tubes; Fig. 7 shows a cascade schematic circuit arrangement for tubes of the class illustrated in Fig. 1; Fig. 8 shows a circuit arrangement embodying the dual compensating principle of my invention, that of compensating for power source and cathode emission change; Fig. 9 illustrates a modified form of bal-

ance circuit embodying my invention; Fig. 9a is a fragmentary diagram illustrating the character of cathode control which may be used in the balance system of my invention; Fig. 10 illustrates the application of a tube of the class illustrated in Fig. 2 applied to the balancing mesh circuit of Figs. 8 and 9; Fig. 11 illustrates the application of a balance circuit operating in accordance with my invention to tubes of the class illustrated in Fig. 1; Fig. 12 shows the balance circuit of my invention employed in connection with a double anode screen grid tube; Fig. 13 shows the balanced amplifier system of my invention using tubes of the class illustrated in Fig. 8 in cascade arrangement; Fig. 14 shows a cascade circuit arrangement illustrating dual compensation with Fig. 1 type of circuit; Fig. 15 illustrates the balancing arrangement for the individual stages applied to a cascade circuit employing a tube of the class illustrated in Fig. 10 in the first stage and a twin triode in the second stage; Fig. 16 illustrates a balancing mesh circuit constructed in accordance with my invention and employing indirectly heated tubes and independently balanced circuits associated therewith; Fig. 17 shows a further cascade system embodying my invention applied to indirectly heated tubes with resistance mesh circuits for balancing the separate stages independently; Fig. 18 illustrates the application of the principles of my invention to a tube circuit having a four-resistance balancing mesh and involving the currents from three electrodes of the tube; Fig. 19 shows a modified arrangement of adjustable mesh which may be employed in the tube circuit of Fig. 18; Fig. 20 shows a balanced circuit arrangement employing a dual functioning tube applied to the circuit of Fig. 18; Fig. 21 illustrates the application of the type of tube illustrated in Fig. 3 to a modified form of a resistance mesh; Fig. 22 shows the manner of cascading modified tube arrangements in a modified cascade circuit; Fig. 23 illustrates a cascade system embodying the principles of my invention in which four-resistance balancing meshes are employed in both stages; Fig. 24 illustrates a dual functioning first-stage tube with a four-resistance balancing mesh circuit coupled to a double auxiliary anode tube second-stage, also balanced with a four-resistance mesh; Fig. 25 shows the balancing circuit of my invention applied to a tube in which a different source is used for the plate and screen grid as distinguished from the source used for the filament or heater element; Fig. 26 shows a modified resistance mesh circuit used for a tube

including a screen grid and a shield grid where separate sources are used for the plate and screen grid as distinguished from the source used for the filament or heater; Fig. 27 illustrates the application of the principles of my invention to a tube employing, in addition to control, screen and suppressor grids, a space charge grid, an anode and a filament where the plate and screen grid voltages are held constant while the emission of the filament is held constant by use of an independent source; Fig. 28 shows a circuit embodying the principles as set forth in the circuit of Fig. 27 but illustrating a heater type tube instead of a directly emitting cathode; and Fig. 29 shows a modified circuit for a tube similar to Fig. 27.

Referring to the drawings in detail, reference character 1, in Fig. 1, designates a three electrode electron tube including cathode 2, control grid 3 and anode 4 with an auxiliary anode 5 included in the tube. The auxiliary anode 5 has a relatively low potential impressed thereon and serves as a means for preventing oscillation and stabilizing the operation of the amplifier circuit. The power supply circuit for energizing the circuits of the electron tube 1 is connected across terminals 6. A series circuit extends from terminals 6 through resistor 7 and adjustable resistors 8 and 23 to the cathode 2 as shown. Another series path extends from anode 4 through adjustable resistor 9 to the positive side of the potential source at one of the terminals 6. The input circuit to the tube is indicated at 10 connected at one side to control grid 3 and at the other side through resistor 7 to the cathode 2. The output circuit is shown at 11 connected at one side to auxiliary anode 5 and at the opposite side to a point 12 between adjustable resistors 8 and 23. A resistor 14 is connected at one end to high potential point 15 and at the other end to the auxiliary anode 5. The drop in potential across resistor 14 is impressed on auxiliary anode 5 for effecting balanced operation of the circuit. The input circuit may be regulated by placing a regulating resistance across the input circuit 10. Meters may be arranged in series with the power supply circuit and shunted across the output of each stage for adjusting the balanced relation of the several circuits. The circuits of the meters shunted across the output are opened during operation. Balance of any one stage can be made by the meter in the output of the following stage, thus obtaining the balance with actual operating conditions. The auxiliary anode 5 is electronically coupled with the electrodes 2, 3 and 4. Resistors 7, 8, 9, 14 and 23 are determined to give the preferred characteristics and best operation conditions. When adjustments for balance and compensation for voltage changes are made the input is turned off. The grid bias from the voltage drop in 7 is obtained by a closed path in the input circuit. The final adjustment for balance and compensation for changes in the power source are made by adjusting 8, 9 and 14. In Fig. 7 I have shown how tube circuits of the class shown in Fig. 1 may be cascaded. I have shown in the second stage similar elements to those described with prime designations added to the reference characters.

In Fig. 2 I have illustrated the same arrangement of resistors in circuit with the electrodes of the tube, but in this instance I employ a grid-like anode 16 interposed between the cathode and the control grid 3 and anode 4 and directly in the electron discharge path. The output circuit is similar to the arrangement of the output cir-

cuit in the system of Fig. 1. The balancing is effected in the same way that the balancing is obtained in the system of Fig. 1. The particular advantage of the circuit of Fig. 2 is that the output is taken from points of very low D. C. potential.

By applying the principles of my invention to multi-stage amplifier systems, a circuit arrangement of the type illustrated in Fig. 3 is secured. I have shown the coupled system employing a pentode in which there is introduced in addition to the electrodes illustrated in Fig. 1, the suppressor grid 17 and the screen grid 18. The second tube of the coupled system is indicated at 1' and contains electrodes similar to the electrodes of tube 1 and are correspondingly numbered with a prime character as shown. The power supply circuit for the multi-stage system is shown generally by a source 19 connected through adjustable regulating resistance 20 to the series circuit extending from terminal 21 through adjustable resistor 22 to adjustable resistor 8 and thence through adjustable resistor 23 to the cathode 2 through adjustable resistor 7, returning to the source 19. Resistor 79 which shunts the cathode 2 enables less current to be used by the filament in the first stage than in the second and takes care of the current through resistor 22 not passing through the filament of the second stage. Similar use is made of resistor 79 in Figs. 6 and 7, and of resistor 49 in Fig. 13, for example. Suppressor grid 17 connects to the cathode circuit as indicated at 24. Screen grid 18 connects to a point in the power supply circuit as indicated at 26 through adjustable resistor 52. Adjustable resistor 9 is included between anode 4 and point 26 in the series circuit. The coupling resistor 14 connects between high potential point 15 and the auxiliary anode 5 of tube 1. The circuit of my invention allows paralleling of the two stages and therefore a lower potential power supply may be used. The complete load of the plate circuit is also utilized. The auxiliary anode 5 serves as the balancing means in cooperation with the adjustable resistors and the regulated input at 10. The circuit of the second tube 1' is similar to the circuit of tube 1. A connection extends from one end of resistor 14 to control grid 3'. The suppressor grid 17' connects to the cathode circuit of cathode 2' as indicated at 24'. The screen grid 18' connects to terminal 26' in the output circuit through resistor 52'. Auxiliary anode 5' connects to one end of resistor 14' while anode 4' connects to the other end of resistor 14' as indicated at 15'. The preferred characteristics and operating conditions are more flexible with a pentode in that the additional resistance 52 can be adjusted and with a coupled circuit the relative voltage on the two stages can be regulated by resistor 22. The preferred characteristics, balance and compensation for power source changes are obtained in a manner similar to that stated for Fig. 1.

In Fig. 4 I have shown the principles of my invention applied to twin triode tubes indicated at 27 and 27'. Each of these tubes contains a cathode shown at 28 and 28' heated by filaments 29 and 29', respectively. The heating filaments 29 and 29' are energized by the same power source as that indicated at D. C. The tubes contain control grids 30 and 31 and 30' and 31', respectively. The tubes contain anodes 32 and 33 and 32' and 33', respectively. Separate input circuits are provided for the control grids 30 and 31 of tube 27 as represented at 34 and 35, respec-

tively. The power supply circuit is connected in a manner similar to the power supply circuit shown in Fig. 3 and includes resistor 22, adjustable resistors 8 and 23 and resistor 7 with adjustable resistors 8' and 23' arranged in parallel with adjustable resistors 8 and 22 for obtaining the required potential for the plate supply system of tube 27'. Anodes 32 and 33 are connected to opposite ends of coupling resistor 14 and to the high potential point 15 which connects through adjustable resistor 9 to point 26 in the power supply circuit. The additional anode functions simultaneously to effect amplification, balance and compensation of power source changes. When the same input is placed on both 34 and 35 the combined amplification of both sides of the tube is obtained on the input of the second stage. When two inputs are being impressed they are combined on the second stage. In this circuit twin tubes function as twin tube amplifiers and simultaneously balance out voltage variations. The preferred characteristics, balance and compensation are obtained in a manner similar to that stated for Fig. 1. The elements in the second stage of amplification constituted by tube 27' are arranged similarly to the arrangement of elements and the circuits therefor illustrated in connection with tube 27 except that control grids 39' and 31' are connected together and to one end of coupling resistor 14. Anodes 32' and 33' connect across opposite ends of resistor 14' and to high potential point 15' as shown. The balancing and compensating condition is obtained similarly to that of the first stage.

Fig. 5 illustrates the application of the principles of my invention to twin pentode tubes shown at 36 and 36'. The twin pentode tubes have in addition to the elements illustrated in Fig. 4, suppressor grids 37 and 38 and screen grids 39 and 40. Similarly, tube 36' includes suppressor grids 37' and 38' and screen grids 39' and 40'. The external circuit arrangement is similar to the circuit described in connection with Fig. 4. It will be seen that the suppressor grids 37 and 38 connect to the point 41 in the cathode circuit which contains cathode 28. Similarly, suppressor grids 37' and 38' connect to point 41' in circuit with cathode 28'. Separate adjustable resistors 46 and 47 are disposed in the conductors leading to screen grids 39 and 40 for tube 36 from point 42 in the output circuit and in the case of tube 36', adjustable tap resistors 46' and 47' are included in the conductors leading to screen grids 39' and 40' from point 42' in the output circuit. Resistances 46 and 47 are placed in the circuit to obtain the correct potentials on grids 39 and 40. Resistors 23 and 8 are separate variable resistances, 23 functioning to change the tube circuit characteristics and 8 functioning directly to adjust for balance. The circuits are balanced and a high degree of stability is obtained in the system of Fig. 5 by adjustment of resistors 8-23-22-46-47 and 8'-23'-46'-47' to those values which give the preferred characteristics of the tube and circuit for balance and best operation. That is to say, the characteristics of stage one are changed by adjusting 23, 7, 46, and 22. When the preferred characteristics are obtained then 8, 9 and 14 are adjusted until a constant grid bias on the second stage is maintained when the voltage of the power source changes. The second stage or in general the last stage is then adjusted for balance in the usual way for zero potential across

the output when zero potential is across the input. In this circuit twin pentodes are used in place of the twin triodes shown in Fig. 4, the corresponding elements being connected in this circuit in exactly the same way. The suppressor and screen grids do not enter into the balancing part of the circuit but the screen grid voltage-control resistors 47, 46, 47' and 46' give this circuit additional flexibility to obtain preferred characteristics and operating conditions. The balance and compensation are obtained in a manner similar to that for Fig. 4.

My invention is applicable to coupling circuits for multiple electrode tubes generally as indicated in Fig. 6. A tube circuit similar to the circuit of Fig. 2 has been illustrated where each tube 44 and 44' has a screen grid in place of the space charge grid, and includes in addition to the electrodes illustrated in connection with the circuit of Fig. 2, a suppressor grid 17 and 17', respectively. Suppressor grid 17 connects to point 24 in circuit with cathode 2, while suppressor grid 17' connects to point 24' in circuit with cathode 2'. Balanced operation of each circuit is obtained by adjustment of the power supply circuit through resistor 20, and by adjustment of resistors 7, 8 and 23, and 8' and 23' to those values to give preferred characteristics of the tube and circuit for balance and best operation. A high degree of stability is obtained and operation of the amplifier circuit effectively controlled.

I have heretofore described the balancing of coupled stages when each stage is balanced separately. It is not necessary to balance each stage separately, that is the first stage can serve in its entirety as a unit affecting the tube circuit characteristics of the second stage and then the second stage can be balanced in the usual way for maintaining zero output with zero input for varying power source potentials. Under these conditions the grid bias on the second stage changes with the power source voltage change similar to the way it changes in the first stage where the current change in resistor 7 produces a bias change.

With certain tubes balance of both stages may not be possible separately but the two stages as a unit invariably can be balanced as a high degree of flexibility has been introduced into the system with the introduction of another tube. The grid bias on the second stage can thus be made to vary any desirable way giving as much negative slope to the characteristics between the current in the balancing mesh of the last stage as is needed. The twin tubes employed in the circuits of Figs. 4 and 5 show, in addition to other advantages, that the same elements can serve simultaneously to balance and amplify.

In Fig. 8 an amplifying circuit of my invention is shown in which the output is balanced and this balance maintained by the dual compensating action of the circuit with power source changes and independent changes in the emission of the cathode other than those due to that of the power source. The tube shown is a diode-triode with a filament cathode 2, control grid 3, triode anode 4 and diode anode 5. In normal operation the power source 19 is connected in series with the regulating resistance 20, adjustable resistors 8 and 23, the filament 2, switch 53 in a position and adjustable resistor 7. When adjustment for change in emission compensation is made, switch 53 is thrown in *b* position and resistances 48 and 49 are adjusted so

that the same current goes through resistors 7, 23 and 8, but less through the filament than when the switch is in the *a* position. The input is connected between the end of resistor 7 and the control grid 3. The grid bias, due to drop in resistor 7, is maintained on the grid through a closed path in the input circuit. Adjustable resistor 9 is connected between anode 4 and one end of resistor 8, while the other anode 5 is connected to the other end of resistor 8 through adjustable resistors 50 and 43. The output is taken from anode 4 and the connection between resistors 50 and 43. Resistors 8, 9 and 43 form a three-resistance balancing mesh with the output. The resistances 7, 8, 9, 43, 23 and 50 are determined experimentally and by calculation, as explained later, to give tube circuit characteristics that will give balanced and dual compensating conditions. The final adjustments are made in the resistances so that both a change in adjustment of resistor 20 and a shift of switch 53 from position *a* to position *b* produces no change in the reading of a meter placed across the output connections. While adjusting for balance and compensation, the input is turned off.

Fig. 9 shows the same circuit as Fig. 8, adapted to a diode-triode heater type of tube.

Fig. 9a shows an alternative arrangement of the heater circuit which can be used when the power transformer has good voltage regulation. With the arrangement shown in Figs. 9 and 9a the final adjustments are made in the resistances so that there is no change in the reading of a meter placed across the output, both when resistor 45 is adjusted and the voltage on the primary of the power transformer is changed.

Fig. 10 is a circuit similar to that shown in Fig. 8 except that space charge grid 16 is used in place of the diode anode 5. The adjustments and operations of this circuit and this tube are similar to those stated for that shown in Fig. 8.

Fig. 11 shows the circuit illustrated in Fig. 1 arranged for balancing and dual compensation. Similarly to the circuit illustrated in Fig. 8, resistors 8, 9 and 14 form a three-resistance balancing mesh with the output. The balancing and dual compensating conditions are found in a manner similar to that described for Fig. 8.

Fig. 12 shows a further modification of my invention in which balance and compensation for both changes in the power source and changes in the emission of the cathode, independent of the power source, are obtained at the output by means of a circuit using a four-resistance balancing mesh at the output. A diode-tetrode is shown with filament cathode 2, tetrode anode 4, control grid 3, screen grid 18, and diode anode 5. The circuit is an extension of the circuit shown in Fig. 11 in that in place of one of the terminals of the output being from the connection between resistors 8 and 23, this connection is connected to the screen grid through two adjustable resistors 51 and 50 in series, and this terminal of the output taken from the connection between resistors 50 and 51. In this circuit the currents of two elements besides that from the principal anode are involved in the balancing mesh and, as is shown later in the theoretical discussion gives still more flexibility by allowing balance at zero potential on the output, when the input is off, to be maintained with both changes in the power source and independent changes in the emission for large ranges of characteristics of the tube cir-

cuits. In this circuit the values of all the resistances of the circuit are determined by a combination of experiment and calculation to give best operating conditions and tube circuit characteristics that will balance. Final adjustments are made on resistances 8, 9, 14 and 51 so that no change in a meter placed across the output is produced when resistance 20 is adjusted and switch 53 is thrown from position *a* to position *b*.

Fig. 13 illustrates how circuits of the class shown in Fig. 8 may be cascaded. The elements of the second stage are designated by the corresponding primed reference figures. Adjustable resistor 22 enables a lower anode voltage to be used on the first stage than on the second stage, while adjustable resistor 55 enables additional flexibility to be obtained. Resistor 49 across the filament of the first stage enables less current to be used in filament of the first stage than in the second and takes care of the current through resistor 22 not passing through the filament of the second stage. The first stage is balanced so that a constant bias is maintained on the grid of the second stage with change of both cathode emission and power source. The resistors of this stage are determined for the preferred characteristics and best operation, and then the resistors 8, 9 and 43 are adjusted until the balance and dual compensating conditions are obtained. This is discussed further in the theoretical discussion. The balance and dual compensating condition is obtained on the second stage in a manner similar to that explained for Fig. 8.

In Fig. 14 is illustrated how circuits of the class shown in Fig. 11 may be cascaded. The discussion above on Fig. 13 also applies to this circuit.

In Fig. 15 a circuit of the class shown in Fig. 10 is coupled with a circuit of the class of Fig. 11 except that a twin-triode is used in place of the diode-triode shown in Fig. 11. The extra grid 25', however, only serves to give greater flexibility to the tube circuit characteristics of the second stage. This grid obtains its bias from the drop in resistor 55 but does not function in the amplification other than its effect on the characteristics. The operation of this circuit is similar to the circuit of Fig. 13 except that similar to the circuit of Fig. 14, the output is taken from points of lower potential than that of the circuit of Fig. 13. The same explanation for balance and dual compensation given for the circuit of Fig. 13 applies here.

In Fig. 16 it is shown how the circuit of Fig. 15 is adapted to similar heater types of tubes.

In Fig. 17 it is shown how the circuit of Fig. 14 is adapted to heater types of tubes. The first stage is exactly similar but in the second stage a twin-triode is used in place of the diode-triode of Fig. 14. However, the two circuits are similar. The extra grid 25' obtains its grid bias from the drop in resistor 55 similar to that of the circuit of Fig. 15. Aside from the greater flexibility it derives by having this grid, it is the same type of circuit as that illustrated in Fig. 14 and functions similarly.

In Fig. 18 is shown another modification of my invention in which a four-resistance balancing mesh, similar to that of Fig. 12, is used to obtain the dual compensation. A diode-triode with two diode anodes 70 and 71 is shown. The currents of these two anodes are involved in the balancing and dual compensation. This circuit is also an extension of that of Fig. 11, where

anode 70 corresponds to anode 5, anode 71 is connected to anode 70 through adjustable resistor 57 and the output terminal is then taken from anode 71 instead of from the connection at 72, as in the circuit of Fig. 11. All of the explanation given for Fig. 12 applies to this circuit except that in this circuit resistor 57 replaces 51 in the balancing adjustments. The theoretical discussion of this circuit is given later and differs slightly from that of Fig. 12. This circuit has the advantage of having the output taken from points of relatively low potentials.

In Fig. 19 is shown a still further modification of my invention in which a four-resistance balance mesh, similar to that of Fig. 12, is used to obtain the dual compensation. This circuit is an extension of the circuit shown in Fig. 8 where the diode anode 70 replaces 5. The extension comes in by connecting the additional diode anode 71 to the connection between resistors 43 and 50 through adjustable resistors 56 and 58 in series and taking the output from the connection between resistors 56 and 58 instead of between resistors 43 and 50. All of the explanation given for Fig. 12 applies here, while the theoretical discussion is the same as that for Fig. 18.

In Fig. 20 is shown how the circuit illustrated in Fig. 18 is adapted to a triode-pentode tube. For balancing and compensation the triode anode 5 replaces one of the diode anodes 70, and screen grid 18 replaces the other diode anode 71 of Fig. 18. The pentode suppressor grid 17 is connected directly to the cathode. If the same input is placed on triode control grid 30 and pentode control grid 3, the combined amplification is obtained in the output by the reactances of resistors 14 and 9. This circuit functions simultaneously to give twin amplification, balance and dual compensation.

Fig. 21 shows a still further modification of my invention in which balance and dual compensation are obtained. A diode-pentode is illustrated with filament cathode 2, control grid 3, screen grid 18, suppressor grid 17, pentode anode 4 and diode anode 5. The series circuit through the cathode and power supply 19 is the same as that for Fig. 12. Anode 4 in this circuit is connected to the connection between resistors 8 and 23 through adjustable resistor 51. Anode 5 is connected to positive terminal of the power supply through adjustable resistor 9 and screen grid 18 is connected to anode 5 through adjustable resistor 14. The output is taken from the pentode anode 4 and screen grid 18. Resistors 14, 8, 9 and 51 form a four-resistance balancing mesh at the output. The same theoretical discussion and explanation as given for Fig. 12 applies to this circuit also.

Fig. 22 illustrates a two-stage, balanced, dual-compensating circuit in which the first stage is the same as the first stage of that of Fig. 15, while the second stage is an extension of that of Fig. 15 to a four-mesh balancing circuit. The tubes of this circuit are of the heater type and a triode-pentode in the second stage of this circuit replaces the twin-triode of that of Fig. 15. All the explanation and theoretical discussion given for the first stage of Fig. 15 applies to the first stage of this circuit. The extension in this circuit is that in place of taking one of the terminals of the output from the connection between resistors 8 and 23 the screen grid is connected to this connection through resistors 51'

and 50' and the output taken from the connection between 51' and 50'. The suppressor grid 17' is connected to the cathode. The explanation given for the circuit of Fig. 12 applies to the second stage of this circuit where resistor 51' corresponds to resistor 51.

Fig. 23 illustrates a two-stage, balanced, dual-compensating amplifier with a diode-pentode arranged in a circuit like that of Fig. 18 for the first stage, and a second stage similar to that of Fig. 22. The extra screen grid 18 in this circuit, which is not in that of Fig. 18, is not in the four-resistance balancing mesh. This is accomplished by paralleling resistors 8 and 23 with adjustable resistors 59 and 60, and then connecting grid 18 through resistance 50 to the connection between 59 and 60. With this arrangement there are two independent balancing meshes, the four-resistance balancing mesh, with resistances 8, 9, 14 and 51, which are balanced to maintain a constant grid bias on the next stage, and the two-resistance balancing mesh with resistances 50 and 59, which is independently balanced to maintain a constant positive potential on the screen grid. The resistances of the first stage circuit and the potential for the screen grid are determined by experiment and calculation so that the preferred characteristics and best operating conditions are obtained. The final adjustments are made in resistors 8, 9, 14 and 57 so that a constant grid bias is maintained on the second stage, with an adjustment of 45 and the voltage regulator on the primary of the power pack transformer when the input is turned off. A theoretical discussion of this is given later. The input is then turned on and 50, 59 and 60 adjusted until the desired constant voltage is maintained between the cathode and grid 18 with change in the input. The theoretical discussion of this two-resistance balancing mesh is also given later. The explanation given for the second stage of the circuit of Fig. 22 applies to this second stage.

Fig. 24 illustrates a two-stage amplifier, each stage of which has two balancing meshes in which, together, they compensate for three variations. A space charge tetrode-pentode is used in the first stage with the same circuit as that shown in Fig. 23, where space charge grid 16 replaces anode 71. All the explanation given for the first stage of Fig. 23 applies to this first stage. This has the additional advantage of giving combined amplification with input on control grids 30 and 3, while simultaneously compensating for power source changes and cathode emission at its output, and so that input does not change the screen grid voltage. The second stage is the same as the first stage of Fig. 23. All of the explanation given for the first stage of Fig. 23 applies here except that the balance is maintained at zero when the input is turned off of the first stage of this circuit.

I have shown certain two, three, and four-resistance balancing meshes and several combinations of these where a single power source is used. These show the principles of my invention and some of the ways in which it can be applied. These principles can be applied in many other ways.

In Fig. 25 I have shown an independent source 74 for supplying the cathode heating current for the cathode 2 and also for securing the bias potential for control grid 3. An independent source 75, with regulating resistor 29', is employed for furnishing the plate potential. Adjustable re-

sistors 80 and 9 are arranged in a two-resistance balancing mesh as shown. These two resistors are adjusted until a change in resistor 20' produces no change in the reading of a meter between the cathode and anode. By this means a constant voltage is maintained on the plate when the power source changes. The theoretical discussion of this circuit is given later. The cathode emission change due to variations of power source 14, is compensated for in the usual grid bias method by the variation of the voltage drop in resistor 7. This shows the application of the compensating principle of my invention to holding triode amplifiers constant with variable power sources.

In Fig. 26 is illustrated the principle of my invention applied to maintaining constant potentials on both the anode and screen grid 77 of a pentode. The circuit is similar to that of Fig. 25 except that an independent provision is made to maintain a constant potential on the screen grid with the variation of the power source. For this, adjustable resistors 8 and 23 are shunted across 80 and the screen grid connected to their junction through resistor 43. Resistors 43 and 23 then are adjusted to compensate for the power source change so that a constant potential is maintained on the grid. For tubes in which the screen grid potential and plate can be the same the output between the screen grid and plate can be used for D. C. amplification or direct coupling. Resistors 8, 9, 43, 23 and 80 can be so adjusted to maintain the same potential on both grid 77 and anode 4 with change of power sources with the input off. The output variation will be proportional to the input and independent of the power source changes. As an A. C. amplifier with capacitance or other indirect coupling the preferred voltages on the screen grid and anode can be maintained and the output between the cathode and anode is preferred.

In Fig. 27 an amplifier is illustrated in which a tube similar to that of Fig. 26 is used which, in addition to the cathode 2, anode 4, control grid 3, screen grid 77, suppressor grid 78, contains a space charge grid 76. The space charge grid, with the cathode, acts as an emission source. The emission from this source is maintained constant with power source and other changes by adjusting resistors 7, 81, 82 until no change occurs in the emission when both switch 53 is thrown from position *a* to position *b* and resistor 20 is adjusted. The anode-screen grid part of the circuit is the same as that illustrated in Fig. 26 and all of the explanation given for the circuit of Fig. 26 applies to this circuit.

Fig. 28 illustrates the circuit of Fig. 27 applied to a similar heater type of tube.

Fig. 29 is another variation of the circuit of Fig. 26.

In Figs. 1, 2, 3, 4, 5, 6 and 7, the output, with resistors 8, 9 and 14 form a circuit mesh which is to be balanced. Consider the potential drop across resistance 14 as *E*, the resistances 8 and 9 as *R*₁ and *R*₀, respectively, and the currents in *R*₁ and *R*₀ as *I*₁ and *I*₀, respectively. The factors affecting the balance of the bridge are the currents *I*₀ and *I*₁. These currents are each dependent on a common factor, which is the source of potential of the system, and the effects thereof may be made to neutralize each other for any variations in the potential source by properly adjusting the resistance of the circuit.

It will be appreciated that the same principles are involved in both a direct heated cathode cir-

cuit device, and the indirect cathode heating system as long as all power is obtained from the same source. There is a simultaneous change in the heating of the cathode, and the plate potential under conditions of changes in the common power supply. Accordingly, variation in cathode emission due to variation of power supply in the circuit shown in my invention will be balanced similar to the direct heated system.

10 The values of the two resistances 9 and 8 represented by *R*₀ and *R*₁, respectively, depend upon the characteristics of the tube and circuit. The simplest way to determine this dependence is to regard the output circuit across resistance 14 as having a voltage drop designated *E*, and the resistances *R*₀ and *R*₁ as a Dowling zero shunt. When a current *I*₀ is passing through *R*₀ and a current *I*₁ through *R*₁, then the requirement for no current through the output circuit is:

$$R_0 I_0 + E = I_1 R_1 \text{ or } R_1 = (R_0 I_0 + E) / I_1 \quad (1)$$

Now for the circuit to be balanced for a change ΔI_0 in *I*₀ and a corresponding change ΔI_1 in *I*₁, the following equation must hold:

$$R_0 (I_0 + \Delta I_0) + E = R_1 (I_1 + \Delta I_1) \quad (2)$$

Substituting for *R*₁ from (1) :

$$R_0 (I_0 + \Delta I_0) + E = (R_0 I_0 + E) (I_1 + \Delta I_1) / I_1$$

$$30 R_0 \left(I_0 + \Delta I_0 - I_0 - \frac{I_0}{I_1} \Delta I_1 \right) = E \left(1 - 1 + \frac{\Delta I_1}{I_1} \right)$$

Cancelling and rearranging:

$$R_0 (I_1 \Delta I_0 - I_0 \Delta I_1) = + E \Delta I_1$$

or

$$35 R_0 = \frac{E \Delta I_1}{-I_0 \Delta I_1 + I_1 \Delta I_0} = \frac{E}{-I_0 + I_1 \frac{\Delta I_1}{\Delta I_0}} \quad (3)$$

The above is the value of *R*₀ for balanced conditions in terms of *E*, *I*₁, *I*₀ and the slope of the *I*₁ vs. *I*₀ characteristics. *R*₁ is then determined by Equation 1.

If *E*, the voltage drop across resistance 14, is constant and it can be considered as a first approximation as constant, because the effect on it of a change in electron emission is counteracted by the effect on it of the change in potential drop across resistance 23 caused by a simultaneous change in *I*₁, it is evident that the characteristics must be such that the denominator is a constant for all values of *I*₀ in order that *R*₀ can be a constant. By putting the denominator in differential form equating it to a constant and solving the differential equation, we obtain the characteristics of *I*₁ vs. *I*₀ necessary to have *R*₀ a constant as follows:

$$I_0 - I_1 (dI_0/dI_1) = k_1 \quad (4)$$

$$I_1 (dI_0/dI_1) = I_0 - k_1$$

$$\int \frac{dI_0}{I_0 - k_1} = \int \frac{dI_1}{I_1}$$

$$\log (I_0 - k_1) = \log I_1 + \log k_2$$

$$\log (I_0 - k_1) = \log k_2 I_1$$

$$I_0 = k_2 I_1 + k_1 \quad (5)$$

Equation 5 is the general equation of a straight line. Therefore, if the portion of the characteristics near the operating value of *I*₀ is straight, the circuit will balance and remain balanced.

The length of this straight portion determines the range of external fluctuations that can be balanced. This requirement is usually fulfilled for normal operating conditions. This one-tube circuit affords so simple a means of balancing external tube variations that it is as easily set up as an unbalanced circuit, will operate much more satisfactorily, and with refinements, will

balance as closely as the two-tube circuit. The advantages over the two-tube circuit are: the elimination of the difficulty in balancing, of extra apparatus, and of the necessity of obtaining exactly similar tubes, which are not readily procurable.

The balancing in these circuits is accomplished by adjusting resistances R_0 , R_1 , and voltage E . Without voltage E , the circuit would not balance even though it appears the drop $R_0 I_0$ could be made to balance drop $R_1 I_1$. This is not possible, as can be seen by allowing E to equal zero in the first equation after Equation 2, which will then cause R_0 to cancel out of the equation and thereby eliminate the means of adjusting for balance. To have a voltage drop E in the circuit R_0 , R_1 , and the output, is an essential feature of the circuit of my invention.

The actual values of the resistances R_0 and R_1 need not be calculated from Equations 3 and 1, but can be determined experimentally as follows: A suitable D. C. electric current meter is placed across the output terminals with R_0 not far from the expected correct value and R_1 is adjusted until the meter reads zero. The supply current is then increased by increasing the voltage into the supply circuit and the deflection of the meter noted. Then, with a new value of R_0 (a value which differs from the expected correct value in the opposite direction from that of the first value taken), R_1 is again adjusted for zero reading of the meter, and the deflection of the meter again noted for an increase in supply current. If the correct value of R_0 for balance is near the value which was expected, this second deflection will be in the opposite direction to the first. Values of R_0 between these two are then taken and the above procedure repeated until a value of R_0 and R_1 is found for which no deflection is produced in the meter when the supply current is changed. Every tube even of the same type and make differs enough in characteristics to require the values of R_0 and R_1 to be determined experimentally for balance against supply power changes.

The assumption that E is constant is introduced to simplify the discussion and to show the fundamental idea of balancing against changes in supply power. Actually, the assumption of E being constant is an unnecessary assumption and can be replaced by the assumption that the resistances 14, 9 and 8 remain constant which can always be accurately fulfilled.

The following discussion will show that the circuit of my invention will balance, not approximately, but completely for normal operating voltages on the tube and that the conditions are not altered from those just given, 14 being any suitable constant resistance, and R_0 and R_1 determined experimentally in exactly the same way as before. Call resistance 14, R_2 ; and the current through it, I_2 . Then, for balance at some current I_0 with the corresponding currents I_1 and I_2 , the following equation must hold:

$$R_0 I_0 + R_2 I_2 = I_1 R_1$$

or

$$R_0 = \frac{I_1 R_1 - R_2 I_2}{I_0} \quad (6)$$

Now to remain balanced when I_0 changes to $I_0 + \Delta I_0$ causing I_2 to change to $I_2 + \Delta I_2$ and I_1 to $I_1 + \Delta I_1$, the following equation must hold also:

$$R_0(I_0 + \Delta I_0) + R_2 I_2 + R_2 \Delta I_2 = I_1(I_1 + \Delta I_1)$$

substituting R_0 in this, gives

$$\frac{I_1 R_1 - R_2 I_2}{I_0}(I_0 + \Delta I_0) + R_2 I_2 + R_2 \Delta I_2 = R_1(I_1 + \Delta I_1)$$

Cancelling and rearranging, gives

$$R_1(I_1 \Delta I_0 - I_0 \Delta I_1) = R_2(I_2 \Delta I_0 - I_0 \Delta I_2)$$

or

$$\frac{R_1}{R_2} = \frac{I_2 \Delta I_0 - I_0 \Delta I_2}{I_1 \Delta I_0 - I_0 \Delta I_1} = \frac{I_2 - I_0 \frac{\Delta I_2}{\Delta I_0}}{I_1 - I_0 \frac{\Delta I_1}{\Delta I_0}} \quad (7)$$

This is a similar condition to that of the previous case, the denominator having exactly the same form. Here, the numerator also has exactly the same form. In order for the denominator to remain constant with change of I_0 and I_1 , it was shown that the only requirement was that the $I_1 - I_0$ characteristics must be linear in the operating region, so here in order that the numerator remains constant with change of I_0 and I_2 , the $I_2 - I_0$ characteristics must also be linear in the operating region. These two conditions are practically always met in amplifying tubes.

As it is the ratio

$$\frac{R_1}{R_2}$$

25 that must fit the requirement of the characteristics of the tube given by Equation 7, the resistance R_2 can be chosen arbitrarily within the operating range and R_0 and R_1 determined experimentally in exactly the same way as indicated in the simplified discussion.

If, in place of solving first for R_0 in Equation 6, R_1 is obtained as follows:

$$R_1 = \frac{R_0 I_0 + R_2 I_2}{I_1} \quad (8)$$

and then it is eliminated in place of R_0 , the second condition of balance,

$$\frac{R_2}{R_0} = - \frac{I_0 - I_1 \frac{\Delta I_0}{\Delta I_1}}{I_2 - I_1 \frac{\Delta I_2}{\Delta I_1}} \quad (9)$$

is obtained.

45 From this, it is seen that R_0 can just as well be chosen arbitrarily in place of R_2 and then R_2 and R_1 adjusted for the balance condition experimentally in exactly the same way as R_0 and R_1 were. This is a more convenient method of 50 adjusting, as during adjustment, the tube can be held closer to its operating voltages. As R_0 is arbitrary, a special case of this circuit is when $R_0 = 0$.

55 So far, it has been shown that these circuits will completely balance out changes in the supply power sources. It will be shown now that further adjustments of these circuits of my invention are possible, whereby the circuits will balance both changes in the power source, and changes 60 in cathode emission due not only to variations in the power supply, but to any cause, as for example, the deterioration of the cathode or filament.

To compensate for cathode emission change, due to other than power source change, a means must be introduced into the circuit whereby the emission of the cathode can be changed independently of the power source. This is accomplished by introducing a series resistance S in the filament or heater circuit designated by 48 and a shunt resistance S designated by 49 in the circuits, as shown in Fig. 8, for example. The filament or heater resistance may be designated h when the cathode is emitting normally i. e. the switch is in position a and h' when the cathode

is emitting less electrons or the switch 53 is in position *b*; the *s* and *S* should be adjusted so that

$$\frac{1}{S+h'} + \frac{1}{s} = \frac{1}{h}$$

This is accomplished experimentally for any desired decrease in emission by merely adjusting *S* and *s* so that the meter 54 will read the same with the switch in position *b* as it did with the switch in position *a*. With this adjustment the emission is changed but the resistances of the circuits, except those of the tubes changed by the emission, remain constant. This is a means of producing a change in cathode emission independently of the power source change. Therefore if the tube is balanced so that there is no change in the output when switch 53 is thrown from position *a* to position *b* the tube, when being operated normally i. e. with switch in position *a*, will remain in balance if the cathode emission changes for any reason whatsoever.

An alternative way of securing this independent change of emission for heater types of tubes when the voltage regulation of the power transformer used in the power pack is good, is merely to adjust resistance 45 shown in Fig. 9a.

The voltage of the power source is changed—to obtain adjustment of the circuit for balance of no change in the output when the power source changes—by adjusting resistance 20 for filament type of tubes and by adjusting any kind of voltage regulator before the power transformer for heater types of tubes.

It is by these means possible to make independent changes in the electron emission of the cathode and the voltage of the power source. I will designate this variable emission property of the cathode by the variable *X* and the voltage of the source by variable *E*. These two variables are independent and effect all the currents in the tube circuit. It is to be noted that both *E* and *X* change the cathode emission and in general all the currents and voltages of the circuit, but that each functions independently.

Resistances 8, 9 and 43, in Figs. 8-10 and 13 and the first stages of Figs. 15, 16 and 22, and resistances 8, 9, and 14, in Figs. 11, 14 and 17 and the second stages of Figs. 15 and 16, together with the output, form a mesh of the circuit that is now to be balanced for no change in output when both independent changes of electron emission properties of the cathode and changes of power voltage source are made. The resistances 8, 9, and 43, and 8, 9, and 14 and the corresponding primes, may be designated *R*₁, *R*₀ and *R*₂ respectively and the corresponding currents *i*₁, *i*₀ and *i*₂.

The conditions for balancing when only the power source changes are discussed above and in the parent application Serial Number 732,170, filed June 23, 1934, now Patent 2,166,184, and show that for proper adjustments the balance will hold in the linear part of the tube circuit characteristics. It was also shown by experiment that such characteristics as *i*₁—*i*₀ are linear through a large range of values. We will consider now the conditions for balance for the linear part of the tube circuit characteristics. This discussion will therefore hold in general, the only limitation being on the range of variation of *E* and *X* for which the circuit will remain balanced. It is found that with some tubes a high degree of balance can be maintained over a range of variation of better than 10%.

The equations for the currents are then of the form *i*=*a*+*nE*+*mX* or specifically

$$\begin{aligned} i_0 &= a_0 + n_0 E + m_0 X \\ i_1 &= a_1 + n_1 E + m_1 X \\ i_2 &= a_2 + n_2 E + m_2 X \end{aligned}$$

which are equations of tube circuit characteristics.

$$10 \quad \frac{\partial i}{\partial E} = n \text{ and } \frac{\partial i}{\partial X} = m$$

so the *n*'s are the partial derivatives with respect to *E* and *X* respectively.

The total change in any current is given by

$$15 \quad di = \frac{\partial i}{\partial E} dE + \frac{\partial i}{\partial X} dX \text{ or } di = ndE + mdX$$

The partial change in currents due to a change in *E* alone is *(di)*_{*E*}=*ndE* and that due to a change in *X* alone is *(di)*_{*X*}=*mdX*. From this it is seen that if the circuit is adjusted so that it remains balanced for the same adjustment for both a change in *E* and a change in *X* it will remain balanced for the combined change of *E* and *X*.

The equation for no voltage across the output is

$$(1) \quad R_0 i_0 + R_2 i_2 = R_1 i_1$$

The equation that the changes in voltages in this circuit will compensate for change of *E* is

$$30 \quad (2) \quad R_0 (di_0)_E + R_2 (di_2)_E = R_1 (di_1)_E$$

The corresponding equation for change of *X* is

$$(3) \quad R_0 (di_0)_X + R_2 (di_2)_X = R_1 (di_1)_X$$

By substituting the values of the *(di)*_{*X*}'s and *(di)*_{*E*}'s and cancelling the *dE*'s and *dX*'s respectively, Equations 2 and 3 become

$$(2) \quad R_0 n_0 + R_2 m_2 = R_1 n_1$$

$$(3) \quad R_0 m_0 + R_2 n_2 = R_1 m_1$$

40 Putting in the values of *i*₀, *i*₁ and *i*₂ in Equation 1 it becomes

$$(1) \quad R_0 (a_0 + n_0 E + m_0 X) + R_2 (a_2 + n_2 E + m_2 X) = R_1 (a_1 + n_1 E + m_1 X)$$

45 Multiplying Equation 2 by *E* and Equation 3 by *X*, adding them together and subtracting their sum from (1) gives

$$a_0 R_0 + a_2 R_2 - a_1 R_1 = 0$$

50 This equation, together with Equations 2 and 3, gives the independent equations of this circuit mesh for the conditions sought.

$$n_0 R_0 + n_2 R_2 - n_1 R_1 = 0$$

$$m_0 R_0 + m_2 R_2 - m_1 R_1 = 0$$

55 This is a set of linear, homogeneous equations which only have a solution if the determinant of the set of equations is zero, or

$$60 \quad D = \begin{vmatrix} a_0 & a_2 & -a_1 \\ n_0 & n_2 & -n_1 \\ m_0 & m_2 & -m_1 \end{vmatrix} = a_1 n_2 m_1 + a_2 n_0 m_1 + a_0 n_2 m_1 - a_0 n_2 m_1 - a_2 n_1 m_0 - a_1 n_0 m_2 = 0$$

65 The tube circuit characteristics are given by the values of these *a*'s, *n*'s and *m*'s. The above equation indicates the requirements of the tube circuit characteristics that must be met in order that the circuit can be balanced for power supply voltage change and change in cathode emission properties. These characteristics can be varied by adjusting 7, 20, 23, 50 and the actual power supply voltage. When this requirement of the characteristics is met then for any given

70 value of *R*₁, the correct values of *R*₀ and *R*₂ can

be calculated from any two of the equations as follows:

$$R_0 = \frac{n_0 R_0 + n_2 R_2 - n_1 R_1}{m_0 R_0 + m_2 R_2 - m_1 R_1}$$

$$R_0 = \frac{\begin{vmatrix} n_0 & n_2 \\ m_0 & m_2 \end{vmatrix} - R_1(n_1 m_2 - n_2 m_1)}{\begin{vmatrix} n_0 & n_2 \\ m_0 & m_2 \end{vmatrix} - n_0 m_2 - n_2 m_0}$$

$$R_2 = \frac{\begin{vmatrix} n_0 & n_1 R_1 \\ m_0 & m_1 R_1 \\ n_0 & n_2 \\ m_0 & m_2 \end{vmatrix} - R_1(n_0 m_1 - n_1 m_0)}{\begin{vmatrix} n_0 & n_2 \\ m_0 & m_2 \end{vmatrix} - n_0 m_2 - n_2 m_0}$$

This same analysis holds for circuits, Figs. 1, 2, 3, 4, 5, 6, 7 and all the circuits in the parent patents with three-resistance balancing mesh, if resistances 48 and 49 and switch 53 are inserted in the circuit.

All these circuits can then be balanced for both change of emission properties of the cathode and change in power supply voltage if the characteristics of the tube circuit are obtained experimentally and then varied until

$$a_1 n_2 m_1 + a_2 n_0 m_1 + a_0 m_2 n_1 - a_0 n_2 m_1 - a_2 n_1 m_0 - a_1 n_0 m_2 = 0$$

holds. The desired value of R_1 (that which gives a sufficient amplification) being used, the correct values of R_0 and R_2 are then calculated from the above equations. The final adjustments can be made experimentally by making slight adjustments of the various resistances until no change in the output occurs with either a change of 53 from a to b or with an adjustment of the power supply voltage.

It is to be noted that a set of linear homogeneous equations is formed because we are balancing for zero and have just as many resistances in the balancing mesh as we have independent conditions. When a set of homogeneous equations is obtained, then balance for all changes can only be obtained when the circuit is adjusted so that a definite relation between the tube circuit characteristics is obtained. Any change in the conditions required that will produce a set of linear equations any one of which is non-homogeneous will remove the requirement of a definite relation between the tube circuit characteristics and therefore allow balance for a large range of desirable characteristics merely by adjusting the three resistances in the balancing mesh.

In Figs. 13, 14, and 15, when each stage is balanced separately, the circuits for the first stage must be balanced so that a constant negative bias for the second stage is maintained on the output of the first stage. This requirement makes the first equation non-homogeneous. That is, $R_{01} + R_{21} - R_{11} = \epsilon$ where ϵ is positive in Fig. 14 and negative in Figs. 13 and 15. There is no change in the compensating equations so the three independent equations are:

$$a_0 R_0 + a_2 R_2 - a_1 R_1 = \epsilon$$

$$n_0 R_0 + n_2 R_2 - n_1 R_1 = 0$$

$$m_0 R_0 + m_2 R_2 - m_1 R_1 = 0$$

This set of equations has a unique solution if

$$D = \begin{vmatrix} a_0 & a_2 & -a_1 \\ n_0 & n_2 & -n_1 \\ m_0 & m_2 & -m_1 \end{vmatrix} \neq 0$$

So this stage can be balanced for any relation

between the characteristics except the one that was previously required for zero. The solution of these equations is

$$R_0 = \frac{\begin{vmatrix} \epsilon & a_2 & -a_1 \\ 0 & n_2 & -n_1 \\ 0 & m_2 & -m_1 \end{vmatrix}}{D} = \frac{\epsilon(n_1 m_2 - n_2 m_1)}{D}$$

$$R_1 = \frac{\begin{vmatrix} a_0 & a_2 & \epsilon \\ n_0 & n_2 & 0 \\ m_0 & m_2 & 0 \end{vmatrix}}{D} = \frac{\epsilon(n_0 m_2 - n_2 m_0)}{D}$$

$$R_2 = \frac{\begin{vmatrix} a_0 & \epsilon & -a_1 \\ n_0 & 0 & -n_1 \\ m_0 & 0 & -m_1 \end{vmatrix}}{D} = \frac{\epsilon(n_0 m_1 - n_1 m_0)}{D}$$

20 This same analysis holds for any second stage also if it is not undesirable to have a fixed constant potential superimposed on the output. For A. C. amplification this is not objectionable and in some D. C. amplifiers.

25 This same analysis holds for all three-resistance balancing mesh circuits shown in this patent and the parent patents if the provisions for adjusting for cathode emission properties as indicated in this patent are made in the circuits. Any tube circuit with at least a three-resistance balancing mesh shown in this patent or the parent patents can be coupled with any other such tube circuit and each stage separately balanced for both these changes.

30 35 The importance of the tube circuit characteristics is shown in this discussion. The way the circuit shown in Fig. 15 is arranged enables large flexibility in the characteristics of the current from the auxiliary balancing element of

40 45 the second stage to be made. The negative potential on the grid 25' can be varied quite arbitrarily and so can be adjusted that any necessary characteristics to effect balance can be obtained. It can readily be seen that with such a circuit, adjustment of 55, which is quite arbitrary, will make it possible to meet the requirements for zero potential to be maintained on the output with almost any tube when no input is impressed on the first stage.

50 Referring again to the set of homogeneous equations set up from the three-resistance balancing mesh, when balanced for zero output with zero input, it was shown that the set would be made non-homogeneous by changing the requirements to a balance for a constant voltage ϵ across the output. When the set of equations is non-homogeneous then balance is possible without a definite relation between the tube circuit characteristics.

55 60 Now if it is desirable to get this double compensating condition and still have a balance for zero voltage across the output, it is necessary to introduce an additional current and resistance in the balancing mesh of the circuit. Any four-resistance balancing mesh will give the flexibility desired so that a balance for both the power source voltage variation and cathode emission property variation can be effective for the maintenance of a zero voltage on the output inde-

70 pendent of a definite relation between the tube circuit currents characteristics. With such a tube circuit, resistances other than the resistance in the balancing mesh, together with the voltage, are adjusted until the desirable characteristics are obtained and then the resistances of the bal-

ancing mesh adjusted until the balanced condition is obtained. This result is indicated mathematically by using an equation in which the sum of the voltage drops across all the resistances in the balancing mesh is equated to zero. This equation, together with the two compensating equations, form a set of non-homogeneous linear equations for which there is a unique solution of three of the resistances in terms of the fourth and the tube circuit characteristics.

Circuits with four-resistance balancing meshes are shown in Figs. 12, 18, 19, 20, 21, 22, 23 and 24. In Figs. 12 and 21 and the second stages of Figs. 22 and 23, consider 9, 8, 14 and 51, in Fig. 19, consider 9, 8, 14 and 56 and in Figs. 18, 20 and 24 and the first stage of Fig. 23, consider 9, 18, 14 and 57 as resistances R_0 , R_1 , R_2 , and R_3 respectively, and i_0 , i_1 , i_2 and i_3 as the corresponding currents. For balance $i_0R_0 + i_2R_2 = i_1R_1 + i_3R_3$.

$$i_0 = a_0 + n_0E + m_0X$$

$$i_1 = a_1 + n_1E + m_1X$$

$$i_2 = a_2 + n_2E + m_2X$$

$$i_3 = a_3 + n_3E + m_3X$$

For compensation, similarly as before, we have

$$n_0R_0dE + n_2R_2dE = n_1R_1dE + n_3R_3dE$$

$$m_0R_0dX + m_2R_2dX = m_1R_1dX + m_3R_3dX$$

and similarly as before we obtain from these equations the three independent equations

$$(1) a_0R_0 + a_2R_2 - a_1R_1 - a_3R_3 = 0$$

$$(2) n_0R_0 + n_2R_2 - n_1R_1 - n_3R_3 = 0$$

$$(3) m_0R_0 + m_2R_2 - m_1R_1 - m_3R_3 = 0$$

Now as R_0 is the plate resistance of the tube, it can be chosen for a desirable amplification and so the other resistances determined in terms of R_0 . The three equations therefore become

$$(1) a_1R_1 + a_3R_3 - a_2R_2 = a_0R_0$$

$$(2) n_1R_1 + n_3R_3 - n_2R_2 = n_0R_0$$

$$(3) m_1R_1 + m_3R_3 - m_2R_2 = m_0R_0$$

This is a set of non-homogeneous linear equations, and they have a unique solution if

$$D = \begin{vmatrix} a_1 & a_3 & -a_2 \\ n_1 & n_3 & -n_2 \\ m_1 & m_3 & -m_2 \end{vmatrix} = 0$$

Then

$$R_1 = \frac{1}{D} \begin{vmatrix} a_0 & a_3 & -a_2 \\ n_0 & n_3 & -n_2 \\ m_0 & m_3 & -m_2 \end{vmatrix}$$

$$R_2 = \frac{1}{D} \begin{vmatrix} a_1 & a_3 & a_0 \\ n_1 & n_3 & n_0 \\ m_1 & m_3 & m_0 \end{vmatrix}$$

$$R_3 = \frac{1}{D} \begin{vmatrix} a_1 & a_0 & -a_2 \\ n_1 & n_0 & -n_2 \\ m_1 & m_0 & -m_2 \end{vmatrix}$$

More particularly, in Figs. 18, 20, 23 and 24, resistors 9, 8, 14 and 57, and in Fig. 24 resistors 9', 8', 14' and 57', may be designated R_0 , R_1 , R_2 , and R_3 respectively and the corresponding currents through them i_0 , i_1 , i_2 and i_3 . Then sim-

ilarly as above we have $R_0i_0 + R_2i_2 + R_3i_3 = R_1i_1$ and the three independent equations are

$$(1) -a_1R_1 + a_2R_2 + a_3R_3 = -a_0R_0$$

$$(2) -n_1R_1 + n_2R_2 + n_3R_3 = -n_0R_0$$

$$(3) -m_1R_1 + m_2R_2 + m_3R_3 = -m_0R_0$$

$$D = \begin{vmatrix} -a_1 & a_2 & a_3 \\ -n_1 & n_2 & n_3 \\ -m_1 & m_2 & m_3 \end{vmatrix}$$

and

$$R_1 = \frac{1}{D} \begin{vmatrix} -a_0 & a_2 & a_3 \\ -n_0 & n_2 & n_3 \\ -m_0 & m_2 & m_3 \end{vmatrix}; R_2 = \frac{1}{D} \begin{vmatrix} -a_1 & -a_0 & a_3 \\ -n_1 & -n_0 & n_3 \\ -m_1 & -m_0 & m_3 \end{vmatrix};$$

$$R_3 = \frac{1}{D} \begin{vmatrix} -a_1 & a_2 & -a_0 \\ -n_1 & n_2 & -n_0 \\ -m_1 & m_2 & -m_0 \end{vmatrix}$$

The tube circuit characteristics, that is the a 's n 's and m 's of the circuits, are obtained experimentally for the preferable values of all the resistances of the circuit except $8=R_1$, $14=R_2$, and 51 , 56 or $57=R_3$ and then the values of these resistances are determined from the above equation. The final adjustments are made experimentally by slight adjustments until the exact values at which a change in E and X will produce no change in the output.

A four-resistance balancing mesh compensating for changes of power-source voltage and cathode emission properties and maintaining a constant voltage on the output with zero voltage on the input, is a similar condition to the case of maintaining zero voltage on the output. If a voltage ϵ is to be maintained on the output of any stage which is to produce the grid bias for a second stage when the input is zero, as for example the first stage of the circuits of Figs. 23 and 24, then the balancing equation will be $R_0i_0 + R_2i_2 + R_3i_3 = R_1i_1 + \epsilon$ and Equation 1 will be

$$(1) -a_1R_1 + a_2R_2 + a_3R_3 = \epsilon - a_0R_0$$

The compensating equations will not change so the solution will be

$$R_1 = \frac{1}{D} \begin{vmatrix} \frac{\epsilon}{R_0} - a_0 & a_2 & a_3 \\ -n_0 & n_2 & n_3 \\ -m_0 & m_2 & m_3 \end{vmatrix}; R_2 = \frac{1}{D} \begin{vmatrix} -a_1 & \frac{\epsilon}{R_0} - a_0 & a_3 \\ -n_1 & -n_0 & n_3 \\ -m_1 & -m_0 & m_3 \end{vmatrix}$$

$$R_3 = \frac{1}{D} \begin{vmatrix} -a_1 & a_2 & \frac{\epsilon}{R_0} - a_0 \\ -n_1 & n_2 & -n_0 \\ -m_1 & m_2 & -m_0 \end{vmatrix}$$

D has the same value as before. The solution for the other type of four-resistance circuit would be similarly changed for this condition.

Multiple stage amplifiers can be formed out of any combination of any four-resistance balancing mesh circuits and a separate power-source used for each stage or the same power-source used for any combinations of stages. The complete compensation of E and X changes can be adjusted for in each separate stage as described above, since all four-resistance balancing meshes for any condition of balancing fall into one of the four above cases.

Further, multiple stage amplifiers can be formed out of any combination of any three or

four resistance balancing mesh circuits and as long as only one power-source is used in a stage, the same power-source can be used for more than one stage, the complete compensation of E and X changes can be adjusted for in each separate stage, since any stage will fall under some one of the two three-resistance and the four four-resistance balancing mesh cases described.

Although I have not shown all possible circuit embodiments of my invention, I have shown representative circuits and have described various methods by which compensation for E and X are possible for any balancing condition of the output.

It is desirable with A. C. inputs on tubes having screen grids in order that they function as screens that the voltage on the screen grid should remain constant with high resistances in the circuit where there are no condenser by-passes.

The first stage of the circuit shown in Fig. 23 and both stages of the circuit of Fig. 24 show in addition to a four-resistance balancing mesh for the output balance a two resistance balancing mesh for maintaining a constant voltage on the screen grid. Considering resistance 50 as R_4 and resistance 59 as R_5 , the corresponding currents are i_4 and i_5 and the constant voltage to be maintained between cathode and screen grid is E_s . It is only necessary to compensate for the variation of input e as this is the only rapid change. The screen grid current

$$i_s = i_4 = k(\mu e + E_s) + b$$

in the operating range of the tube. Call $k\mu = 14$ and $kE_s + b = a_4$ then, $i_4 = a_4 + l_4 e$ and as i_5 changes similarly with e , we can also write $i_5 = a_5 + l_5 e$.

For a balance at a constant voltage E_s

$$(1') R_5 i_5 - R_4 i_4 = E_s$$

For compensating with change in e to maintain constant E_s

$$(2') R_5 d i_5 - R_4 d i_4 = 0$$

Now

$$\frac{d i_4}{d e} = l_4$$

and

$$\frac{d i_5}{d e} = l_5$$

$$R_5 \frac{d i_5}{d e} = R_4 \frac{d i_4}{d e}$$

or

$$(2) R_5 l_5 = R_4 l_4 \text{ and } (2'') l_2 R_5 e = l_4 R_4 e$$

$$(1'') R_5 (a_5 + l_5 e) - R_4 (a_4 + l_4 e) = E_s$$

subtract (2'')

$$(1) a_5 R_5 - a_4 R_4 = E_s$$

$$(2) l_5 R_5 - l_4 R_4 = 0$$

These equations have a unique solution if

$$D = \begin{vmatrix} a_5 - a_4 \\ l_5 - l_4 \end{vmatrix} = a_4 l_5 - a_5 l_4 \neq 0$$

Then

$$R_5 = \frac{\begin{vmatrix} E_s - a_4 \\ 0 - l_4 \end{vmatrix}}{D} = \frac{-l_4 E_s}{a_4 l_5 - a_5 l_4}$$

and

$$R_4 = \frac{\begin{vmatrix} a_5 & E_s \\ l_5 & 0 \end{vmatrix}}{D} = \frac{-l_5 E_s}{a_4 l_5 - a_5 l_4}$$

By changing the voltage on the input and with meters in the i_4 and i_5 circuits the characteristics a_4 , a_5 , l_4 and l_5 are found and the values of R_4 and R_5 calculated by the above expressions.

By adjusting resistance 60 the balance can be

obtained with the desirable value for E_s . The balance can also be obtained experimentally by a high resistance voltmeter between cathode and screen and adjusting resistances until no change in the reading of the voltmeter is noticed when the input e is changed.

This method can be applied to any set up of two-resistance balancing mesh where a constant voltage is to be maintained. When a different source is used for the plate and screen grid from that used for the filament or heater as in Figs. 25 and 26, this type of circuit can be used to compensate for the changes of the voltage E across 15 and 20 so that the screen and plate voltages are held constant. The cathode emission is held constant by adjusting 1 so that it compensates for changes of emission due to change in the voltage e across 14 and 20 while the two-resistance balancing mesh compensates for change in E . By substituting E for e and calling resistor 23 = R_5 and resistor 43 = R_4 , the two-resistance balancing mesh discussion just given holds for the screen grid circuit of Fig. 26. Similarly if E is substituted for e , E_p , the anode voltage for E_s , resistor 80 = R_5 and resistor 9 = R_4 , the above discussion holds for the two-resistance balancing mesh anode circuits of Figs. 25 and 26.

In Figs. 27, 28 and 29 the plate and screen voltages are held constant similarly to above while the emission is held constant both for changes in e and the cathode emission property X by adjustment of the control grid bias resistor 7 and the resistors in the space charge grid circuit. Output II is used for A. C. amplification with other than direct coupling on any case where a constant voltage impressed on the output is not objectionable while output I, balanced for zero, is used for direct coupling or when a constant voltage impressed on the output is objectionable. These arrangements will hold the amplification constant with any changes of the tube emission, power source and circuit.

One important characteristic of many of the embodiments of my invention is that the coupling is effected between the output of one electrode tube and the input of the succeeding electrode tube at points of low D. C. potential.

While I have described my invention in certain preferred embodiments, I realize that modifications of my invention may be made and I intend no limitations upon my invention other than may be imposed by the scope of the appended claims.

What I claim as new and desire to secure by Letters Patent of the United States is as follows:

1. A balanced amplifier system comprising a four element electron tube including a cathode, an anode, a control grid and an auxiliary anode, an input circuit included between said control grid and cathode, a power supply circuit, resistance elements disposed in said power supply circuit in series with opposite sides of said cathode, an output circuit extending between said auxiliary anode and a point between two of said resistance elements and including an additional resistance element disposed between a point in said power supply circuit and said anode and another resistance element between said anode and said auxiliary anode.

2. A balanced amplifier system comprising a four element electron tube including a cathode, an anode, a control grid and an auxiliary anode, said auxiliary anode being disposed in electronically coupled relation with the said cathode electrode, an input circuit included between said con-

trol grid and cathode, a power supply circuit, resistance elements disposed in said power supply circuit in series with opposite sides of said cathode, an output circuit extending between said auxiliary anode and a point between two of said resistance elements and including an additional resistance element disposed between a point in said power supply circuit and said anode and another resistance element between said anode and said auxiliary anode.

3. A balanced amplifier system comprising a four element electron tube including a cathode, an anode, a control grid and an auxiliary anode, an input circuit included between said control grid and cathode, a power supply circuit, impedance elements disposed in said power supply circuit in series with opposite sides of said cathode, an output circuit extending between said auxiliary anode and a point between two of said impedance elements and including an additional impedance element disposed between a point in said power supply circuit and said anode and another impedance element between said anode and said auxiliary anode.

4. A balanced amplifier system comprising a four element electron tube including a cathode, an anode, a control grid and an auxiliary anode, an input circuit included between said control grid and cathode, a power supply circuit, resistance elements disposed in said power supply circuit in series with opposite sides of said cathode, the resistance elements in circuit with one side of said cathode being disposed in series with said input circuit, an output circuit extending between said auxiliary anode and a point between two of the resistance elements disposed in series with the opposite side of said cathode and including an additional resistance element disposed between a point in said power supply circuit and said anode and another resistance element between said anode and said auxiliary anode.

5. A balanced amplifier system comprising a four element electron tube including a cathode, an anode, a control grid and an auxiliary anode, an input circuit included between said control grid and cathode, a power supply circuit, impedance elements disposed in said power supply circuit in series with opposite sides of said cathode, the impedance elements in circuit with one side of said cathode being disposed in series with said input circuit, an output circuit extending between said auxiliary anode and a point between two of the impedance elements disposed in series with the opposite side of said cathode and including an additional impedance element disposed between a point in said power supply circuit and said anode and another impedance element between said anode and said auxiliary anode.

6. An electron tube amplification system comprising, in combination, a pair of electron tubes each including a cathode, a control grid, an anode and an auxiliary electrode; an input circuit connected between the control grid and cathode of a first of said electron tubes, a resistor interconnecting the anode and the auxiliary electrode of each of said tubes, and a coupling connection between the auxiliary electrode of said first of said tubes and the control grid of the second of said tubes; a source of power, a connection including resistance from the positive terminal of said source to the cathode of said first of said tubes, a connection including resistance from the anode of said first of said tubes and through a portion of the resistance in the last

said connection to the positive terminal of said source of power, a connection including resistance from the positive terminal of said source to the cathode of the said second of said tubes, and 5 a connection including resistance from the anode of the said second of said tubes to the positive terminal of said source; a connection between said cathodes, and means for energizing both said cathodes from said source of power; and 10 an output circuit connected between the auxiliary electrode and the cathode of the said second of said tubes, said output circuit having balanced potentials at the terminals thereof in the absence of signal voltages at said input circuit.

15 7. An electron tube amplification system comprising a pair of twin triode tubes, each having a cathode, a pair of control grids and a pair of coating anodes, a power supply circuit including a series path containing resistors and connections to the series path from said cathodes, independent input circuits connected between the cathode of one tube and the separate control grids thereof, a coupling circuit interconnecting one of the anodes of one of said tubes directly with both said control grids in the other of said tubes, a resistor connected between the other of said anodes in the first said tube and both said grid electrodes in the second said tube, an output circuit including both anode electrodes of the second said tube, and additional resistors in circuit with selected electrodes for balancing the operation of said amplification system, a portion of the circuit between the anodes and cathode of each tube being connected in common with part 20 of said power supply circuit.

30 8. An electron tube amplification system comprising in combination a pair of twin pentodes, each including a cathode, a pair of control grids, a pair of shield grids, a pair of suppressor grids and a pair of anodes, a series power supply circuit including resistors distributed along said circuit and connections to said circuit from said cathodes, separate input circuits extending between the cathode and the control grids of one of said twin pentodes, said input circuits including a common resistor in said power supply circuit, tap connections from said shield grids to points in said power supply circuit, resistors interconnecting a first of the anodes of each twin pentode with points in said power supply circuit, a resistor between the pair of anodes of each twin pentode, a connection between the second of the pair of anodes of one twin pentode and the pair of control grids of the succeeding twin pentode in common, and an output circuit connected between the second of the pair of anodes of the other twin pentode and the cathode thereof, said output circuit having balanced potentials at the terminals thereof in the absence of signal voltages at said input circuits.

35 9. A balanced amplifier system comprising a four element electron tube including a cathode, an anode, a control grid and an auxiliary anode, an input circuit included between said control grid and cathode, a power supply circuit, resistance elements disposed in said power supply circuit in series with said cathode, an output circuit extending between said auxiliary anode and a point between two of said resistance elements and including additional resistance elements disposed between a point in said power supply circuit and said anode and between said anode and said auxiliary anode, and means connected with said cathode for predetermining the effect of

variation in the electron emission of said cathode on conditions of balance of said system.

10. A balanced amplifier system comprising an electron tube including a cathode, an anode, a control grid and a pair of auxiliary anodes, an input circuit included between said control grid and cathode, a power supply circuit, resistance elements disposed in said power supply circuit in series with said cathode, an output circuit extending between one of said auxiliary anodes and a point between two of said resistance elements and including additional resistors disposed between a point in said power supply circuit and said anode and between said anode and the other of said auxiliary anodes and between said auxiliary anodes for balancing said system.

11. An amplification system comprising an electron tube having a cathode and an anode and a multiplicity of grid electrodes, independent power supply sources, an input circuit, one of said power supply sources operating to energize said cathode and in connection with said input circuit to bias at least one of said grid electrodes, another of said power supply sources operating to energize said anode and at least one other grid electrode, and an output circuit comprising a plurality of resistances connected in series between said anode and said other grid electrode, with a connection to the last said power supply circuit from between two of said plurality of resistances, and a connection to said cathode from between another two of said plurality of resistances, for balancing the potentials at the terminals of said output circuit in the absence of signal voltages in said input circuit.

12. In a balanced amplifier system, an electron tube circuit containing successive tubes, a first of said tubes containing a cathode, a main anode, a plurality of grid electrodes and a divided anode having a pair of sections, means for energizing said electrodes, an input circuit individual to each tube including the cathode and control grid thereof, and an output circuit for said first tube comprising four resistances connected in series between one section of said divided anode and said cathode and coupled with the input circuit of the next succeeding tube in said amplifier sys-

tem; one of said resistances being connected directly in circuit with said energizing means, another between said energizing means and said main anode, and the others between said main anode and the said section of the divided anode with a connection therebetween to the other section of said divided anode, for balancing the potentials at the terminals of said output circuit in the absence of signal voltages in the input circuit connected with the said first tube.

13. A balanced electron tube system comprising an electron tube device having at least four electrodes, three of said four electrodes being cold electrodes and one an emitting electrode, a source of potential for energizing all said electrodes, and separate means for deriving potential drops proportional to the currents through each of said cold electrodes and from said source of potential, respectively, said separate means being connected in series relation and having a constant potential relation at the terminals of said series during variations in the potential of said source and resulting variations in emission, and during independent variations in emission.

14. A balanced amplifier system comprising an electron tube device including a screen grid amplifier portion and a diode portion having a common source of electrons in said device, a source of potential for energizing said electron tube device; separate means for deriving potential drops proportional to the currents in said amplifier and said diode portions of said device and from said source of potential, respectively, said separate means being connected in series relation with the terminals of said series constituting output terminals of said system; additional means for deriving a potential drop proportional to the screen grid current in said amplifier portion, and other means for deriving a second potential drop from said source of potential, said additional means and said other means being connected in series relation with a constant potential relation at the terminals of the respective series for supplying a constant screen grid potential to the amplifier portion of said electron tube device.

WALTER SOLLER.
